United States Patent Office

Des. 225,413
Patented Dec. 12, 1972

225,413

TELEPHONE MOUNT

Allen W. Scoggins, 1415 S. Rita Mae Ave.,
Merced, Calif. 95340

Filed June 1, 1971, Ser. No. 149,119

Term of patent 14 years

Int. Cl. D14—03

U.S. Cl. D26—14

FIG. 2

FIG. 1

FIG. 1 is a side perspective view of a telephone mount showing my new design;

FIG. 2 is a front perspective thereof;

FIG. 3 is a top plan view thereof; and

FIG. 4 is a rear perspective thereof.

I claim:

The ornamental design for a telephone mount, substantially as shown.
